High Turner Island Maine

Setton Patent

The Schedule referred to in the Setton Patent and making part of the same containing a description in the words of the said High Turner Island, of the improvement in a machine called a Corn Sheller.

To all whom these presents shall come: Be it known that I High Turner of Hovey in the County of Cumberland in the State of Maine have invented a new and useful improvement in a machine for separating ^{corn from the} cob called the Corn Sheller, and that the following is a full and exact description of the construction and operation of said machine as invented or improved by me.

The top or body of the machine is three feet eight inches long, sixteen inches wide and two feet and six inches high. This box is made of hard wood black oak with one and a half in thickness and fastened by screws to half wood just half a foot long and four inches square in the corners. In the side of this box there is an open space of eight inches high extending the whole length of the box, on the same side of the box there is fitted two posts in the corners a foot of hard wood by two in diameter one inch and a half in thickness and three inches deep in each corner. At the base of these one and a half inch between said box and the side of the box. The bar comes up to the top of the box.

On this bar and the opposite side of the box and exactly in the middle of the box there is put back two, on this box there is ^{upon} a gyroscope made of the same bar one inch square a heavy wheel three feet in diameter with three inches thick as by letters in the annexed drawing. On one side of this wheel there are inserted in circular rows of three each the spokes being three eights of an inch square and pointing from the surface of the wheel five eighteenths an inch. These pins are then placed from three eights to one inch apart. The wheel turns as near the bar as is consistent with the gyroscope and the space between the bar and wheel is one in. There is fastened to the wall of the box

of cast iron or hickory that will fit into the slot of the wheel, and in
the middle it is attached to a nail with a small nail, so as to hold it in the
wheel. By use of turning the crank it gives a rapid motion to the wheel.
The large wheel is also made of cast iron and the belt to which it is attached
is made in leather. These gins now are found down to nine fathoms.

Another engine like this is made of the wood of the tree, this is fitted
with a follow in the form of a dove tail and a pulley wheel to one half of the tree
as before described. This follow is made of hickory wood and a nail in this
is held with a wire into the supports as indicated by the dotted line in the upper
end plane (3,3)(3) the upper half of the tree must be cut out to the half with the
tree plan. Called the follow more or less like a boat. It is made of planks 6 to 8
inches thick with two inches wide. In case of this gins there are inserted three
pieces of strong wood one each in diameter 6 inches, each being twenty three inches
of the log retaining the follow. These pieces of wood are set in the hole in the
bottom of the log so that the pine stream it and the said pine
leaves such as a quince. It is then inserted of the approaching water
by means of a nail to the pine tree. Now when it is necessary to place some
such of these pine pushing forward the follow to the greatest extent. These planks
are made of three pine cuttings of one inch in diameter. 5 pieces of plank
one inches in thickness. Well constructed so that they close and prevent
the water from passing down. A log twenty inches high of the same length of the
other + twelve inches wide made of pine boards one inch in thickness +
are twisted together at the ends and ends. are dressed + nailed at the
top and opened at the bottom so that is held to the log by means
of hedges at each end this is pointed to the end of the cutting of each
joined by cutting a hole through the side of the upper log in a position
just half way between the centre and the right hand end of the log one
foot long and eight inches wide planing diagonally downward in the
inner part of which there is a slide on which the logs of pine are placed
and dropped down when the machine is in motion as will appear by the
letter C. Another slide on the opposite end for such water getting the upper
end properly by cutting the logs by inclining outward, a slide is also
long and eight inches wide passing the logs and brings them out of the

machine separate from the corn. This machine can be worked by hand or horse power. As to the application of machinery and the corn is dropped down the feed horizontally, so fast as a man can pick it up and pass it to the feeder, never at a time I claim as my invention in the feeding the following made of three distinct pieces and the application of the spiral springs to the rollers when applied together with the slide separating the corn from the corn - the upper box preventing the corn from scattering.
